[57] CLAIM

The ornamental design for a portable fastener driving device housing, as shown and described.

DESCRIPTION

FIG. 1 is a perspective view of a portable fastener driving device housing showing my new design, looking at the top, front and left side, the magazine assembly and nosepiece of the device being shown in phantom lines; FIG. 2 is a left side elevational view thereof, the right side thereof being a mirror image thereof; FIG. 3 is a front elevational view thereof; FIG. 4 is a rear elevational view thereof; FIG. 5 is a top plan view thereof; and, FIG. 6 is a bottom plan view thereof. The broken line showing of the magazine assembly and nosepiece is for illustrative purposes only and forms no part of the claimed design.
